ABSTRACT

A frequency conversion system for an electronic musical instrument. The system has a signal source, at least one frequency converter and an electro-acoustic transducer, and converts the fundamental frequency and overtones of each signal generated by said signal source into other frequencies so as to change said signal with said fundamental frequency and overtones into another signal having an inharmonicity function other than and having a natural tone quality, clearness and strength and also to change the pitch of said signal into another pitch which matches the natural pitch sensation recognized by human ears.

FREQUENCY CONVERSION SYSTEM FOR AN ELECTRONIC MUSICAL INSTRUMENT

This application is a continuation of application Ser. No. 865,030, filed Oct. 9, 1969, now abandoned.

5

FIELD OF THE INVENTION

The present invention relates generally to the tone quality of an electronic musical instrument and more particularly relates to a frequency conversion system for getting a new signal the fundamental frequency and overtone frequencies of which are different in harmonicity and pitch from those of the original tone.

DESCRIPTION OF THE PRIOR ART

A conventional electronic musical instrument has been said to be inferior in tone quality to a conventional musical instrument which utilizes mechanical vibration or acoustical vibration. The difference in tone character between an electronic musical instrument and a conventional musical instrument exists for the following reasons. The mechanical vibrations and the acoustical vibrations in a conventional musical instrument generally do not have exact harmonics; that is, the frequencies of the overtones of the vibration are not exactly positive integer multiples of the fundamental frequency of the vibration.

For example, the fundamental frequency f_1 and the frequencies of the harmonics f_n due to the vibration of a piano string can be represented as follows,

$$f_n = n f_0 (1 + n^2 \pi^2 Q^2 S / l^2 T) \quad (1)$$

$$f_0 = C/2l \quad (2)$$

$$C = (T/\rho S) \quad (3)$$

where

l is the free length of the string

T is the tension thereof

ρ is the density thereof

S is the cross section thereof

Q is Young's modulus

k is the radius of gyration about the neutral axis of the cross section

n is the order of the harmonics ($n=1, 2, 3, \dots$)

We can define an inharmonicity function $Y(n)$ as follows,

$$Y(n) = \frac{f_n}{nf_1} = \sqrt{\frac{1+bn^2}{1+b}} \quad (4)$$

where

$$b = \pi^2 Q^2 S / l^2 T \quad (5)$$

$Y(n)$ is a measure of inharmonicity and a ratio of n -th overtone frequency f_n to the multiple n of the fundamental frequency f_1 . As b represented by Equation (5) is generally $10^{-3} \sim 10^{-4}$, so $Y(n)$ becomes no less than 4 percent for a large n .

Equation (4) shows that the greater the order of harmonics, the greater the inharmonicity.

On the other hand, a sound or a signal of a conventional electronic musical instrument generated by an electronic oscillator circuit or a frequency divider circuit has exact harmonics, namely, frequencies of the overtones f_n are exactly positive integer multiples of the fundamental frequency f_1 . The inharmonicity function $Y(n)$ for such a situation is as follows,

$$Y(n) = \frac{f_n}{nf_1} = \frac{nf_1}{nf_1} = 1 \quad (6)$$

Generally, sounds with exact harmonics rarely exist in conventional musical instruments and almost all conventional musical instruments produce sounds with an inharmonicity function other than 1.

10 The tone quality of a signal with inexact harmonics is superior in naturalness, clearness and strength to that of a signal with exact harmonics.

The conventional electronic musical instrument has another defect in that the pitch of the signal does not agree with the natural musical scale. Signals with an exact frequency ratio 2:1 do not sound as though they are at a one octave musical interval to the human ear, especially in a low or a high frequency range but there must be a frequency ratio greater than 2:1 for obtaining a 1 octave musical interval. In a conventional electronic musical instrument, the frequency ratio of two signals which are at a 1 octave musical interval is exactly 2:1 from the low frequency range to high frequency range.

25 As a result, a conventional electronic musical instrument has the defect that the pitch of the signal is not sufficiently high in the high frequency range and is not sufficiently low in the low frequency region.

30 When tone generators are used for every tone signal corresponding to every pitch of the natural musical scale, the defect mentioned above is almost eliminated, although such a method is unnatural because the exact harmonics of each signal are not actually changed into the inexact harmonics of a conventional instrument. Moreover such construction is expensive, bulky and hard to maintain.

SUMMARY OF THE INVENTION

40 It is a primary object of the present invention to provide a frequency conversion system for an electronic musical instrument, said frequency conversion system acting to improve the tone quality of a conventional electronic musical instrument with respect to naturalness, clearness and strength by converting an original signal into a new signal in which the inharmonicity function is other than 1.

45 It is another object of the invention to provide a frequency conversion system which converts an original signal of an electronic musical instrument into a new signal in such a way that the ratios of the frequencies of overtones to the fundamental frequency of the new signal are increased or decreased.

50 A further object of the present invention is to provide a frequency conversion system which improves the pitch of a conventional electronic musical instrument in the low and high pitch regions of the musical scale to reduce the pitch deviation from the natural pitch.

55 These objectives are achieved by employing a frequency conversion system for electronic musical instrument according to the present invention, which comprises a signal source, at least one frequency converter and an electro-acoustic transducer which are connected in series to each other in the described order. A signal from said signal source has the frequency and the pitch converted by said frequency converter and is transduced into a sound by said electro-acoustic transducer.

BRIEF DESCRIPTION OF THE DRAWINGS

The objects and particulars of the present invention will be made clear from the following detailed description of the invention considered together with the accompanying drawings, wherein:

FIG. 1 is a schematic block diagram of an embodiment of a frequency conversion system for an electronic musical instrument according to the present invention;

FIG. 2 is a diagram which depicts an example of the spectrum, i.e. the fundamental frequency and overtone frequencies, of an original signal and a signal which has had the frequency converted;

FIG. 3 is a diagram of the inharmonicity function $Y(n)$ vs. the order of harmonics;

FIG. 4 is a schematic block diagram of a second embodiment of a frequency conversion system for an electronic musical instrument according to the present invention;

FIG. 5 is a schematic block diagram of a third embodiment of a frequency conversion system for an electronic musical instrument according to the present invention;

FIG. 6 is a schematic block diagram of a fourth embodiment of a frequency conversion system for an electronic musical instrument according to the present invention;

FIG. 7 is a schematic block diagram of a fifth embodiment of a frequency conversion system for an electronic musical instrument according to the present invention;

FIG. 8 is a diagram of the characteristic of frequency vs. pitch;

FIG. 9 is a schematic block diagram of a sixth embodiment of a frequency conversion system for an electronic musical instrument according to the present invention;

FIG. 10 is a schematic block diagram of a seventh embodiment of a frequency conversion system for an electronic musical instrument according to the present invention;

FIG. 11 is a diagram of the frequency conversion characteristic of the embodiment shown in FIG. 10;

FIG. 12 is a schematic block diagram of an example of a frequency converter which is used in a frequency conversion system for an electronic musical instrument according to the present invention;

FIG. 13 is a schematic block diagram of a multiplier which is used in the frequency converter shown in FIG. 12;

FIG. 14 is a schematic block diagram of another example of a frequency converter which is used in a frequency conversion system for an electronic musical instrument according to the present invention; and

FIGS. 15A-D is a diagram of a frequency spectrum for explaining the operation of the frequency converter shown in FIG. 14.

DETAILED DESCRIPTION

FIG. 1 is a diagram of a monophonic electronic musical instrument which can produce a new tone.

Referring to FIGS. 1, 2, and 3, in FIG. 1, a signal source 100 comprises a tone generator 98 and a pitch selector 1. The tone generator 98 produces a signal 6 which has fundamental and exact harmonics, i.e., a frequency spectrum $f_1, f_2, f_3, \dots, f_n, \dots$, where the funda-

60

65

mental and harmonic frequencies are f_1 Hz, f_2 Hz, f_3 Hz, $\dots, f_n$ Hz, $\dots$ and

$$f_n = nf_1 \quad (n = 1, 2, 3, \dots)$$

as shown by solid lines in FIG. 2. The fundamental frequency f_1 is controlled by a pitch selector 1. A frequency converter 200 subtracts Δf Hz from the signal 6 and produces a signal 7 having frequency components $(f_1 - \Delta f)$ Hz, $(2f_1 - \Delta f)$ Hz, $(3f_1 - \Delta f)$ Hz, $\dots, (nf_1 - \Delta f)$ Hz, $\dots$ as shown by dotted lines in FIG. 2. The signal 7 is transduced into a sound by an electro-acoustic transducer 3.

The sound has such new tone qualities as naturalness, clearness and strength, and is a new tone which can not be obtained by a conventional electronic musical instrument.

As for the signal 6, the inharmonicity function $Y(n)$ is

20

$$Y(n) = \frac{f_n}{nf_1} = \frac{nf_1 - \Delta f}{nf_1} = 1 - \frac{\Delta f}{nf_1} \quad (7)$$

Therefore the signal 6 does not have a naturalness of a tone produced by a conventional musical instrument. This relationship is shown by a solid line 10 in FIG. 3.

As for the signal 7, the inharmonicity function $Y(n)$ can be represented as follows,

30

$$Y(n) = \frac{nf_1 - \Delta f}{n(f_1 - \Delta f)} = 1 + \left(1 - \frac{1}{n}\right) \frac{\Delta f}{f_1 - \Delta f} \quad (8)$$

35

where $(f_1 - \Delta f)$ is a fundamental frequency and $(nf_1 - \Delta f)$ is the frequency of the n-th harmonic. Equation (8) indicates that the ratios of the frequencies of overtones to the fundamental frequency increase with an increase in the frequency. Equation (8) is shown by a dotted line 11 in FIG. 3. The dotted line 11 shows that a signal 7 has an inharmonicity function somewhat similar to a piano tone, the inharmonicity function $Y(n)$ of which is represented by Equation (4) and is shown by the curved line 12 in FIG. 3. The frequency Δf is preferably a sub-audio frequency, for example, several Hz, for simulation of a piano tone.

When the frequency Δf is less than 2 percent of the fundamental frequency f , the converted signal 7 has an improved tone quality such as improved naturalness, clearness and strength. When Δf is more than 2 percent and less than 4 percent of the fundamental frequency f , the tone quality of the converted signal 7 is further improved with respect to naturalness, clearness and strength. When Δf is more than 4 percent of the fundamental frequency f , the signal 7 has a tone quality that cannot be obtained either by a conventional electronic musical instrument or by the conventional musical instrument.

As mentioned above, a frequency conversion system according to the present invention can change a signal with exact harmonics into another signal with inexact harmonics such as those of the natural sound of a conventional musical instrument.

When the frequency converter 200 adds $\Delta f'$ Hz to the signal 6 in FIG. 1, the converted signal 7 becomes a signal with inexact harmonics and an inharmonicity function $Y(n)$ represented by Equation (9).

$$Y(n) = \frac{nf_i + \Delta f}{n(f_i + \Delta f)} = 1 - \left(1 + \frac{1}{n}\right) \frac{\Delta f}{f_i + \Delta f} \quad (9)$$

Equation (9) shows that the ratios of the frequencies of overtones to the fundamental frequency decrease. Equation (9) is shown by curved line 13 in FIG. 3. This signal is a new one which a conventional electronic musical instrument cannot produce.

FIG. 4 shows a second embodiment of a frequency conversion system for an electronic musical instrument according to the present invention. A signal source 100 is composed of a tone generator 98 and a pitch selector 1. The tone generator 98 the frequency of which is controlled by the pitch selector 1 produces a signal 6 which has fundamental and exact harmonics. A frequency converter 200 increases or decreases the frequencies of the signal 6 by $\Delta f/\text{Hz}$ and puts out a signal 7. The signal 7 is transduced into a sound by an electro-acoustic transducer 3. Frequency $\Delta f/\text{Hz}$ is also controlled by the pitch selector 1. Then, inharmonicity characteristic of the signal 7 is dependent on the pitch of the signal 7 and an optimum inharmonicity function for the signal 7 can be chosen as the pitch of the signal 7 ascends or descends.

FIG. 5 shows the third embodiment of a frequency conversion system for an electronic musical instrument according to the present invention. Referring to FIG. 5, a signal source 100 comprises tone generators 101, 102, 103, 104, ... corresponding to the tones of a musical scale and have fundamental frequencies $f_{101}, f_{102}, f_{103}, \dots$ and their exact harmonics, respectively. The tone generators 101, 102, 103, 104, ... are connected to frequency converters 201, 202, 203, 204, ... respectively. The converting frequencies of the frequency converters 201, 202, 203, 204, ... are $\Delta f_{201}, \Delta f_{202}, \Delta f_{203}, \Delta f_{204}, \dots$ respectively.

The output signals of the frequency converters 201, 202, 203, 204, ... are connected to a keyswitch system 4 of a keyboard. Output signals selected by the keyswitch system 4 are filtered by a tone filter 5 and transduced into sounds by an electro-acoustic transducer 3.

According to the embodiment shown in FIG. 5, any inharmonicity transition is obtainable along the musical scale by arranging the converting frequencies $\Delta f_{201}, \Delta f_{202}, \Delta f_{203}, \Delta f_{204}, \dots$ for desired inharmonicity transition. For example, when the converting frequencies $\Delta f_{201}, \Delta f_{202}, \Delta f_{203}, \Delta f_{204}, \dots$ are the same percentage of the fundamental frequencies of the corresponding tone generators, Equation (8) is the same for every tone generator and frequency converter; in other words, for every tone corresponding to a key of the keyswitch system 4. Therefore, a uniform inharmonicity characteristic is obtained over the whole musical scale.

FIG. 6 shows the fourth embodiment of a frequency conversion system for an electronic musical instrument according to the present invention. Referring to FIG. 6, a signal source 100 comprises tone generators 101, 102, 103, 104, ... corresponding to the musical scale and have fundamental frequencies $f_{101}, f_{102}, f_{103}, f_{104}, \dots$ and their exact harmonics, respectively. Signals from the tone generator 101, 102, 103, 104, ... are selected by a keyswitch system 4. Output signals from the keyswitch system 4 are gathered in one or more groups, for example, in three groups, and further fed to frequency converters 201, 202, and 203 corresponding to the

three groups. Output signals from the frequency converter 201, 202 and 203 are fed to a tone filter 5 and transduced into sounds by electro-acoustic transducer 3. This embodiment requires fewer frequency converters than the embodiment shown in FIG. 5 and is more practical.

FIG. 7 shows a fifth embodiment of a frequency conversion system for an electronic musical instrument according to the present invention to obtain an inharmonicity characteristic in tones. Referring to FIG. 7, a signal source 100 comprises tone generators 101, 102, 103, 104, ... corresponding to the musical scale and having fundamental frequencies $f_{101}, f_{102}, f_{103}, f_{104}, \dots$ and their exact harmonics, respectively. Signals from the tone generators 101, 102, 103, 104, ... are selected by a keyswitch system 4 and fed through resistors 301, 302, 303, 304, ... to a frequency range separator 400 comprising filters and separated into a plurality of groups, for example, into low frequency range signals, medium frequency range signals and high frequency range signals. Separated signals have the frequency converted by frequency converters 201, 202, and 203 respectively which are then gathered by gathering means, i.e. resistors 501, 502 and 503, and further transduced into sounds by an electroacoustic transducer 3.

In the embodiments shown in FIG. 5, FIG. 6 and FIG. 7, pitches or fundamental frequencies of the tone generators 101, 102, 103, 104, ... are preferably biased for compensation of any unwanted pitch deviation caused by the frequency conversion.

A frequency conversion system for an electronic musical instrument according to the present invention has another function and effect which overcomes a defect of the conventional electronic musical instrument, i.e. a discrepancy between the musical scale produced by the conventional electronic musical instrument and a natural pitch sensation.

FIG. 8 shows an example of the relation between the signal frequency and the pitch recognized by human ears. As shown in FIG. 8, the sensation of pitch change saturates in the low and high frequency regions and a greater frequency change is required for human ears to distinguish an equal pitch change in the low and high frequency ranges than is required to distinguish a corresponding change in the middle frequency region.

FIG. 9 shows a sixth embodiment of a frequency conversion system for an electronic musical instrument according to the present invention for correcting the pitch imperfection of a conventional electronic musical instrument. Referring to FIG. 9, a tone generator 99 of a conventional electronic musical instrument generates tone signals which correspond to the musical scale. Generally, the tone generator 99 is composed of twelve oscillators corresponding to the respective tones of the chromatic musical scale and twelve chains of frequency dividers corresponding to said twelve oscillators. For example, when the tone generator 99 comprises oscillators and frequency dividers each of which divides the frequency of an input signal by a factor of two, the one octave musical intervals of the output signals are in the exact frequency ratio of 2:1.

The signals from the tone generator 99 are fed to a frequency converter 200 through a keyswitch 4 and a tone filter 5 and are transduced into sounds by an electro-acoustic transducer 3. The tone generator 99, the keyswitch system 4 and the tone filter 5 compose a sig-

nal source 100. The frequency converter 200 decreases the frequency f Hz of the input signal by Δf Hz and produces a signal with a frequency $(f-\Delta f)$ Hz. The percentage of frequency change η from the original pitch corresponding to the fundamental frequency f Hz of said tone generator 99 is represented as follows:

$$\eta = \Delta f/f \times 100 (\%) \quad (10)$$

η becomes great as the frequency f Hz decreases, i.e., the pitch reduction becomes great as the frequency f Hz decreases. Therefore, a tone in the low frequency range has a sufficiently low pitch and the pitch imperfection is improved in the low frequency range. Because the inharmonicity characteristic is also improved, the tone quality is improved.

FIG. 10 shows a seventh embodiment of a frequency conversion system for an electronic musical instrument according to the present invention for correcting the pitch imperfection of a conventional electronic musical instrument. Referring to FIG. 10, a signal source 100 comprises a tone generator 99, a keyswitch system 4 and a tone filter 5. The tone generator 99 of a conventional electronic musical instrument generates tone signals having frequencies which correspond to the musical scale. The signal from the tone generator 99 is fed to a frequency range separator 40 through the keyswitch system 4 and the tone filter 5, so as to be separated into a plurality of frequency-band-limited signals, for example, into four signals the range of frequencies of which are $(F_1 \sim F_2)$, $(F_2 \sim F_3)$, $(F_3 \sim F_4)$ and $(F_4 \sim F_5)$, respectively, where $F_1 < F_2 < F_3 < F_4 < F_5$, as shown in FIG. 10. At least one signal from the frequency range separator 400, for example, three signals, are fed to sub-frequency converters, for example, 205, 206 and 207, respectively.

Signals from the sub-frequency converters 205, 206 and 207 and the remainder of the frequency-band-limited signal which is not fed to any sub-frequency converter are gathered together through resistors 501, 502, 503 and 504 and further transduced into sounds by an electro-acoustic transducer 3.

The frequency range separator 400, the sub-frequency converters 205, 206 and 207 and resistors 501, 502, 503 and 504 compose a frequency converter 210.

When the converting frequencies of the sub-frequency converters 205, 206 and 207 are Δf Hz, $\Delta f'$ Hz and $\Delta f''$ Hz, respectively, and are in the relation,

$$\Delta f < 0 < \Delta f' < \Delta f'' \quad (11)$$

the pitch defect is improved not only in the low frequency range $(F_1 \sim F_2)$, but also in the high frequency range $(F_3 \sim F_4)$ and $(F_4 \sim F_5)$. A negative converting frequency corresponds to a frequency decrement and a positive converting frequency corresponds to a frequency increment.

FIG. 11 shows an example of the frequency conversion characteristic achieved by the embodiment shown in FIG. 10.

Tone quality is also improved by the inharmonicity characteristic which is obtained. In the embodiments shown in FIG. 9 and FIG. 10, it is best if the tone generator 99 is biased to change the frequency for compen-

sation of unwanted pitch deviation caused by frequency conversion.

When a magnetic tape recorder or a record player for playing record discs is used as a signal source 100 in FIG. 1, FIG. 4, FIG. 9 and FIG. 10, the harmonicity characteristic or the pitch of the signals recorded on the tape or the disc is changed and the tone quality and the pitch imperfection are improved.

When a conventional musical instrument such as a violin, a clarinet or a trumpet and an acoustic-electric transducer such as a microphone are used as a signal source 100 in FIG. 1, FIG. 4, FIG. 5, FIG. 9 and FIG. 10, the inharmonicity characteristic of the musical instrument can be changed and a new tone having better tone quality than the original tone quality can be obtained. Some conventional musical instruments having pitch imperfection can be improved. It is also possible to obtain an entirely new tone quality by converting frequencies of signals of conventional musical instruments.

As mentioned-above, the scope of the present invention is not limited to a particular kind of signal source 100. It is only necessary that the signal source 100 generate an audio frequency signal.

The frequency converters 200, 201, 202, 203, 204, ... and sub-frequency converter 205, 206, 207 can be realized as follows.

FIG. 12 shows an example of a frequency converter. Referring to FIG. 12, an audio frequency signal $A \sin(2\pi ft)$, such as the output signal of an electronic musical instrument, is applied to an input terminal 601 and is split by a constant phase splitter 603 into two signals X_1 and X_2 having a phase difference from each other of $\pi/2$ radians and respectively supplied to leads 605 and 606. Signals X_1 and X_2 from the leads 605 and 606 are fed to multipliers 609 and 610 respectively and are gathered by gathering means, i.e. resistors 611 and 612, and supplied to an output terminal 613. An oscillator 602 generates a pair of frequency converting signals Y_1 and Y_2 having a phase difference of $\pi/2$ radians from each other and supplies them to leads 607 and 608. Signals Y_1 and Y_2 from the leads 607 and 608 are fed to the multipliers 609 and 610 respectively. The signals X_1 , X_2 , Y_1 and Y_2 can be represented as follows.

$$X_1 = A \sin(2\pi ft + \phi) \quad (12)$$

$$X_2 = A \sin(2\pi ft \pm \pi/2 + \phi) \quad (13)$$

$$Y_1 = B \sin(2\pi \Delta ft + \psi) \quad (14)$$

$$Y_2 = B \sin(2\pi \Delta ft + \pi/2 + \psi) \quad (15)$$

Output signals Z_1 and Z_2 from the multipliers 609 and 610 can be represented as follows.

$$Z_1 = X_1 Y_1 = AB \sin(2\pi ft + \phi) \sin(2\pi \Delta ft + \psi) \quad (16)$$

$$Z_2 = X_2 Y_2 = AB \sin(2\pi ft \pm \pi/2 + \phi) \sin(2\pi \Delta ft \pm \pi/2 + \psi) \quad (17)$$

The signals Z_1 and Z_2 are gathered together and a signal $\frac{1}{2}(Z_1+Z_2)$ as represented by Equation (18) appears at the output terminal 613.

$$\frac{1}{2}(Z_1+Z_2) = \frac{1}{2} AB \cos \{2\pi (f \pm \Delta f)t + \phi - \psi\} \quad (18)$$

The signal $\frac{1}{2}(Z_1+Z_2)$ at the output terminal 613 is a signal the frequency of which is the sum of or the difference between the two frequencies from the input terminals 601 and the oscillator 602. Whether the frequency of the signal $\frac{1}{2}(Z_1+Z_2)$ becomes the sum or the difference of the two frequencies depends on the phase difference between the two output signals from the phase splitter 603 and the phase difference between the two output signals from the oscillator 602.

FIG. 13 shows an embodiment of the multipliers 609 and 610. A signal X applied to a terminal 614 is modulated in an amplitude modulator 616 by a modulating signal Y applied to a terminal 617. The signal X is also fed to a phase inverter 615. Output signals from the amplitude modulator 616 and the phase inverter 615 are gathered together by gathering means, i.e. resistors 618 and 619, and appear at an output terminal 620. The output signal from the amplitude modulator 616 has a carrier signal X and its two side bands. When the carrier signal X is cancelled by a phase inverted signal from the phase inverter 615 at the output terminal 620, only two side-bands appear at the terminal 620. The two side-bands correspond to a signal XY, namely, a product of the signal X and the signal Y. The multipliers 609 and 610 and the amplitude modulator 616 should be linear.

An embodiment of a frequency converter which can be used as the frequency converter 200, 201, 202, 203, 204, . . . is shown in FIG. 14. A modulator 623 modulates an audio frequency signal $\{f_a\}$, which is applied to a terminal 621, by a modulating signal f_c which has a frequency higher than $\{f_a\}$ and which is supplied to another terminal 622. The modulator 623 produces at least two side bands $f_c - \{f_a\}$ and $f_c + \{f_a\}$ as shown in FIG. 15(a) and (b). A band pass filter 624 passes only the lower side band $f_c - \{f_a\}$ as shown in FIG. 15(c). Another modulator 626 modulates the filtered lower side band $f_c - \{f_a\}$ by another modulating signal f_c' ($= f_c - \Delta f$) and produces at least two side bands $f_c' - f_c + \{f_a\}$ and $f_c' + f_c - \{f_a\}$ as shown in FIG. 15(d). The lower side band $f_c' - f_c + \{f_a\}$ is passed by another band pass filter 627 and appears at an output terminal 628. The output signal $f_c' - f_c + \{f_a\}$ is $\{f_a\} - \Delta f$ the frequency of which is lower than that of the signal $\{f_a\}$ by a small frequency Δf . The balanced modulators 623 and 627 can be linear modulators such as multipliers using a Hall effect or nonlinear modulators such as ring modulators.

While particular embodiments of the invention have been shown and described, it will be apparent to those skilled in the art that numerous modifications and variations can be made in the form and construction thereof without departing from the fundamental principles of the invention.

We claim:

1. A frequency conversion system for an electronic musical instrument comprising:
a signal source composed of at least one biased tone generator which is detuned from a normal musical scale by a predetermined frequency difference Δf Hz in a predetermined direction for generating a first tone signal having a first fundamental frequency component which is biased from said normal musical scale by said frequency difference Δf Hz in said direction and which also has exact harmonic components the frequencies of which are a positive integer multiple of the frequency of said first fundamental frequency;
at least one frequency converter connected to said signal source for changing all the frequency components of said first tone signal in a direction the opposite of said predetermined direction by a converting frequency equal to said predetermined frequency difference Δf Hz in order to produce a converted tone signal having frequency components consisting of a second fundamental frequency component and inexact harmonics thereof, each of said second fundamental frequency component and said inexact harmonics having a changed frequency which differs from said first fundamental frequency component and said exact harmonics of said first tone signal by said converting frequency Δf Hz of said frequency converter; and
an electro-acoustic transducer connected to said at least one frequency converter.

2. A frequency conversion system for an electronic musical instrument as claimed in claim 1, wherein:
said signal source consists essentially of twelve master oscillators and twelve chains of frequency dividers corresponding to said twelve master oscillators and being coupled thereto, said twelve master oscillators being biased to bias the frequency from the normal chromatic musical scale in an upward direction; and
said frequency converter connected to said signal source changes the frequency of an output signal from said signal source in a downward direction by said converting frequency for compensating a pitch discrepancy from a natural pitch sensation of the human ear.

3. A frequency conversion system for an electronic musical instrument as claimed in claim 1, wherein said tone generator has a pitch selector which controls both the frequency of said tone generator and said converting frequency.

4. A frequency conversion system for an electronic musical instrument as claimed in claim 1, wherein there is a plurality of tone generators corresponding in number to the respective tones of the musical scale, and there is a plurality of frequency converters corresponding in number to the number of said tone generators, respectively.

5. A frequency conversion system for an electronic musical instrument as claimed in claim 1 further comprising a key switch system, and in which there is a plurality of tone generators corresponding in number to the respective tones of the musical scale, said key switch system being connected to said tone generator for selecting tone signals from among said plurality of tone generators and gathering said selected tone signals into a plurality of groups each of which has successive tone signals of the musical scale, said frequency con-

version system having a plurality of frequency converters corresponding in number to said plurality of groups of tone signals, said key switch system being connected to said frequency converters for feeding said gathered tone signals to the respective frequency converters.

6. A frequency conversion system for an electronic musical instrument comprising;

a signal source composed of at least one biased tone generator generating a first tone signal having a first fundamental frequency component which is biased from a normal musical scale by a predetermined frequency difference Δf Hz in a predetermined direction and further having exact harmonic components the frequencies of which are a positive integer multiple of the frequency of said first fundamental frequency;

at least one frequency converter composed of a constant phase splitter connected to said tone generator for splitting said first tone signal into a pair of signals having a phase difference of $\pi/2$ radians, an oscillator for generating a pair of frequency converting signals having said predetermined frequency difference αf Hz and a phase difference of $\pi/2$ radians, a first multiplier coupled to said phase splitter and said oscillator for multiplying one output signal from said phase splitter by one of said frequency converting signals from said oscillator, a second multiplier coupled to said phase splitter and said oscillator for multiplying the other output signal from said phase splitter by the other of said frequency converting signals from said oscillator, and gathering means coupled to said multipliers for gathering the output signals from said first and second multipliers, said frequency converter changing all the frequency components of said first tone signal in a direction the opposite of said predetermined direction by said predetermined frequency difference Δf Hz in order to produce a converted tone signal having frequency components consisting of a second fundamental frequency component and inexact harmonics thereof, said second fundamental frequency component and said inexact harmonics having a changed frequency which differs from said first fundamental frequency component and said exact harmonics of said first tone signal by the converting frequency of said frequency converter, respectively; and

5

an electro-acoustic transducer connected to said at least one frequency converter.

7. A frequency conversion system for an electronic musical instrument comprising;

a signal source composed of at least one biased tone generator which is detuned from a normal musical scale by a predetermined frequency difference Δf Hz in a predetermined direction for generating a first tone signal having a first fundamental frequency component which is biased from said normal musical scale by said frequency difference Δf Hz in a predetermined direction and further having exact harmonic components the frequencies of which are positive integer multiples of the frequency of said first fundamental frequency component;

at least one frequency converter composed of a modulator connected to said tone generator for modulating said first tone signal by a modulating signal having a frequency f_c Hz which is higher than twice the frequencies of said exact harmonic components, a first filter coupled to said first modulator for passing only one side band of the modulated signal from said modulator, a further modulator coupled to said first filter for modulating the output signal from said filter by another modulating signal having frequency f'_c Hz which differs by said predetermined frequency difference Δf Hz from said frequency f_c Hz, and a second filter coupled to said further modulator for passing only the lower side band of the modulated signal from said further modulator; and

an electro-acoustic transducer connected to said second filter of said frequency converter.

mental frequency component and said inexact harmonics having a changed frequency which differs from said first fundamental frequency component and said exact harmonics of said first tone signal by the converting frequency of said frequency converter, respectively; and

an electro-acoustic transducer connected to said at least one frequency converter.

7. A frequency conversion system for an electronic musical instrument comprising;

a signal source composed of at least one biased tone generator which is detuned from a normal musical scale by a predetermined frequency difference Δf Hz in a predetermined direction for generating a first tone signal having a first fundamental frequency component which is biased from said normal musical scale by said frequency difference Δf Hz in a predetermined direction and further having exact harmonic components the frequencies of which are positive integer multiples of the frequency of said first fundamental frequency component;

at least one frequency converter composed of a modulator connected to said tone generator for modulating said first tone signal by a modulating signal having a frequency f_c Hz which is higher than twice the frequencies of said exact harmonic components, a first filter coupled to said first modulator for passing only one side band of the modulated signal from said modulator, a further modulator coupled to said first filter for modulating the output signal from said filter by another modulating signal having frequency f'_c Hz which differs by said predetermined frequency difference Δf Hz from said frequency f_c Hz, and a second filter coupled to said further modulator for passing only the lower side band of the modulated signal from said further modulator; and

an electro-acoustic transducer connected to said second filter of said frequency converter.
